REPLACEABLE CARTRIDGE TYPE FOUNTAIN PEN

Henry E. Morse and Noral A. Nelson, Holland, Mich.,
assignors to Sapphire Products, Incorporated, Holland,
Mich., a corporation of Michigan

Application February 4, 1954, Serial No. 408,105

6 Claims. (Cl. 120—45.4)

This invention relates to ink type of writing instruments and particularly to replaceable ink cartridge writing pens.

A primary object of this invention is the provision of a fountain pen having a pen point holder and replaceable ink cartridge which forms the handle of the pen, and wherein upon the depletion of the ink in the cartridge, the latter may be disconnected from the pen point holder and a new cartridge quickly and easily coupled to the holder to furnish a renewed supply of ink to the pen point. A concomitant object is the provision in such a pen of means which prevent any leakage of ink between the pen point holder and the cartridge, either during the act of coupling a new ink cartridge to the pen point holder, or after the cartridge has been coupled thereto.

Another object of the invention is the provision of a replaceable cartridge for a fountain pen, wherein before attachment of the cartridge to the pen, the cartridge is a sealed element which may be carried or stored for subsequent attachment to the pen point holder without any danger of leakage or drying of the ink supply within the cartridge.

Another object of the invention is the provision of a replaceable cartridge type fountain pen wherein the pen point holder is provided with a threaded cartridge puncturing element, having an ink passage therethrough, which is adapted to thread its way through a pervious wall of the cartridge and project into the hollow body thereof and permit the flow of ink from the cartridge to the pen point through such passageway. A concomitant object is the provision of a threaded pen point holder and a complementary threaded ink cartridge, by means of which threads the holder and cartridge are coupled securely together, and which threads have the same lead as do the threads on the cartridge puncturing element.

Still another object of the invention is the provision of a pen point holder threaded at the rear end to receive in threaded engagement a replaceable ink cartridge, and wherein the pen point holder exhibits a threaded cartridge wall puncturing element so disposed with respect to the threaded portion of the pen point holder that the element does not begin to tap its way through the cartridge wall until the holder and cartridge are partially threaded together.

An advantage of the invention resides in the provision of an ink cartridge which itself forms a portion of the body of the pen when attached to the pen point holder, and thereby the cartridge is adapted to hold a larger supply of ink than is possible if, as with prior pens it must fit within the body of the pen.

A meritorious feature of the invention is the provision of a replaceable ink cartridge having a pervious end wall formed of a plastic disc, inset within a hollow tube like end of the cartridge, and which disc is puncturable by the tapping action of a threaded pen point feed tube as the pen point holder and cartridge are coupled together.

While it is primarily intended that the cartridge be discarded after its ink supply is exhausted, the invention contemplates the reuse of the same cartridge by the re-

2

moval of the punctured disc, the refilling of the cartridge and thereafter the insertion of a new disc to replace the punctured one, and thereafter a reuse of the same cartridge.

In the preferred form the ink cartridge constitutes the barrel or handle of the fountain pen and is replaceable.

Other objects, advantages, and meritorious features will become more fully apparent from the following claims, specification and drawings, wherein:

Fig. 1 is a view of our improved pen partially broken away to show the novel features of construction;

Fig. 2 is an enlarged fragmentary view in cross section of the puncturing element just before it begins to tap its way through the pervious disc of the cartridge;

Fig. 3 is a cross sectional view taken on line 3—3 of Fig. 1;

Fig. 4 is a cross sectional view taken on line 4—4 of Fig. 1;

Fig. 5 is a detail view of the insert received in the puncturing element which divides the interior of the element into an ink passageway and an air passageway; and

Fig. 6 is a modified form of the puncturing element.

In carrying out the objects of our invention, a hollow pen point or nib holder 10 is provided which is interiorly threaded as at 12 at the rear end. This threaded portion terminates interiorly in a shoulder 14, against which is adapted to abut the forward end 16 of the replaceable ink cartridge 18, which is exteriorly threaded as at 20 to be threadedly coupled to the holder as shown in Fig. 1. The walls of the holder are offset outwardly as at 22, and the walls of the cartridge are offset inwardly as at 24, so that the exterior of the assembled holder and cartridge will present a smooth cylindrical surface. The cartridge forms a handle for the holder and a part of the body of the fountain pen when the cartridge and holder are assembled.

Disposed within the pen holder is a pen point or nib 26 which is fed ink from the cartridge through a passageway 28. The passageway 28 is formed of two connected passageways 30 and 32. The passageway 30 is formed by the interior bore of a small tube 34 which is supported by and extends from block end 36 of a feed tube 37 to the nib 26. The block is disposed within the holder and is provided with four ridges or tongues 38 which fit within complementary grooves formed in the walls of the holder. Such tongues and grooves prevent the feed tube 37 from rotating in the holder.

The other passageway 32 which forms the second connected part of the passageway 28 is formed by the interior bore of the exposed portion 39 of the feed tube. Such exposed portion, or what may be termed "cartridge puncturing needle," is tapered to a point and threaded as at 40, and the pitch of these threads correspond to the pitch of the threads formed on the cartridge and the holder at 12 and 20. The needle is an integral part of the end wall of the block 36 of the feed tube 37. Such end wall is indicated at 42 in Figs. 1 and 6. Interiorly of the block is disposed a hard rubber insert 44 which supports the tube 34 in position within the block. An O-ring gasket 45, formed of rubber or the like, encircles the ink feed tube and is disposed within a groove formed in the block as shown in Fig. 1. This gasket is adapted to bear against the inner wall 46 of the cartridge as shown in Fig. 1, and prevent the leakage of ink as hereinafter described.

The passageway 32 within the needle opens outwardly thereof through two ports 48 and 50 through the threads of the needle. Disposed within the feed tube 28, and extending from the ports 48 and 50 to the nib, is an insert 52. The insert is a semi-cylindrical rod of hard rubber or the like provided with a linearly extending capillary groove 54 and a slot 56 at one end, and serves to divide the feed tube into an ink passageway and an air passageway.

The ink passageway is defined by the capillary groove 54 which is of such proportion that capillary action will occur when ink is admitted to one end of it. The air passageway is defined by the cooperation of the inner face of the walls of the tube, as at 58, in Fig. 4, and the flat faces 60 and 62 of the insert. The slot 56 permits the communication of the ink and air passageways with the interior of the cartridge through the ports 58 and 50.

The inner wall 46 of the cartridge terminates at the outer or forward end, at the threaded end of the cartridge, and terminates at the inner or rear end in a shoulder 64, as shown in Fig. 2. Rearwardly of the shoulder there extends the smaller diameter bore 66 which opens into the ink reservoir proper 68 of the cartridge.

Disposed within the bore defined by the cartridge wall 46, and spaced from the threaded end of the cartridge is a puncturable plastic disc or the like 70. This disc is press fitted into the bore so that it abuts the shoulder 64. Because of the press fit of the disc within the bore, no ink will pass out of the cartridge until the disc is punctured.

The disc is punctured by the threaded end of the feed tube or needle as the holder 10 and the cartridge are threaded together.

As the needle or feed tube revolves, or as the cartridge is revolved within the holder, the threaded end of the feed tube is drawn toward the disc by the action of the threads on the cartridge and holder. As the tip of the feed tube engages the disc, it begins to thread or tap its way therethrough. Such tapping continues until the shoulder 14 of the holder abuts the threaded end of the cartridge, whereupon the feed tube, cartridge, and holder are disposed as shown in Fig. 1.

The threaded end of the feed tube is so disposed with respect to the threads of the holder, and the rear end of the holder, that two or three threads of the holder and the cartridge will be engaged before the end of the needle will contact the disc. This relationship is shown in Fig. 2. It will be noted in such figure that two threads are engaged between the cartridge and the holder, and still the threaded end of the feed tube or needle 38 is spaced from the disc 70. Such engagement of the threads of the cartridge and holder before the feed tube begins to tap its way through the disc ensures the proper lateral and perpendicular alignment of the feed tube with respect to the disc and the bore 45 of the cartridge. This alignment of the feed tube with the disc, both laterally and perpendicularly, assures a tight fit of the feed tube in the disc after the tapping operation. If the feed tube was to enter the disc at an oblique angle, or was displaced from the axis of the cartridge, each revolution of the feed tube would tend to enlarge the hole in the disc as the tube tapped its way therethrough.

As before stated, the threads of the needle or feed tube 39 are of substantially the same pitch as the threads on the cartridge and holder. When this fact is considered along with the alignment above mentioned, it is readily understood that after the cartridge and holder are coupled together, as shown in Fig. 1, an ink seal is effected around the needle where it passes through the disc. Such seal is improved by the resiliency of the plastic disc which tends to fill the grooves between the threads and press against the needle.

The ports 48 and 50 in the feed tube are spaced from the tip thereof so that they will not interfere with the initial tapping action of the tube through the disc. Their disposition also prevents plastic shavings that may tend to form by the tapping action of the needle from entering the bore of the ink passageway. The rubber O-ring 45 engages the smooth bore of the cartridge formed by the cylindrical wall 46 after the feed tube has begun to thread its way through the disc. However, it is within the concept of the invention that the O-ring and needle could be so disposed and sized that the O-ring would engage the bore 46 before the needle began to tap its way through the disc. This alternative construction is desirable if the disc is made of relatively non-resilient materials, instead of plastic, which materials may not

form an effective seal about the needle until some of the threads nearer the base of the needle have been tapped into the disc. It has, however, been found entirely satisfactory to dispose the O-ring as shown when a plastic disc is employed because there is no ink leakage around the needle as it is tapped into the disc, even in the initial stages of the tapping operation.

The O-ring gasket shown in the drawings is particularly useful if the cartridge and holder should become 10 partly uncoupled before the ink supply is exhausted as where the cartridge is inadvertently partially unscrewed from the holder. And again, the O-ring will prevent any ink leakage if for some reason ink should pass around the needle and seep downwardly toward the 15 block.

It is to be noted that the replaceable cartridge 18 itself forms the barrel or handle of the pen when it is coupled to the nib holder. Because of this the pen will hold a greater supply of ink than is possible with 20 replaceable cartridge type fountain pens wherein the cartridge is enclosed within, and separate from, the barrel or handle. Such use of the cartridge as the barrel or handle of the pen is made possible by the relatively long threads of the cartridge and holder which couple 25 the two together in a rigid connection. As pointed out hereinabove, if because the cartridge does form the barrel or handle of the assembled pen, it should become partially unthreaded from the pen point holder during use of the pen, the O-ring gasket bearing against the 30 interior bore 46 of the barrel 18 will prevent the escape of ink from between the barrel and pen point holder.

Fig. 6 shows a slight modification of the needle 39 heretofore described. In Fig. 6 only the tip of the needle is threaded as at 72 with the threads terminating at the 35 edge of the ports 48' and 50'. Between the threaded end of the needle and the end wall 42' of the block the needle has a smooth cylindrical outer wall 74. In this modification, such smooth wall 74 is received in the opening tapped through the disc 70 by the threaded end 40 of the needle. It has been found that in some instances the termination of threads 72 just ahead of ports 48' and 50' will prevent shavings from the disc from entering the ports.

What we claim is:

1. A cartridge type fountain pen comprising: a pen point holder interiorly threaded at one end; a hollow ink cartridge exteriorly threaded at one end to be threadedly coupled to the holder; an ink feed and cartridge puncturing tube mounted on the threaded end of the holder; a previous disc disposed within the hollow threaded end of the cartridge spaced from the end thereof to be punctured as the holder and cartridge are coupled together; said tube being threaded at its free end with the pitch of the threads corresponding to the pitch 55 of the threads on the holder and cartridge and the threaded end of the tube being adapted to be tapped through the disc and form a seal therewith as the cartridge and holder are threaded together; and a sealing ring encircling the tube and adapted to bear against the interior walls of the cartridge between the end thereof and the disc when the cartridge and holder are threaded together.

2. A cartridge type fountain pen comprising: a pen point holder having a threaded end; a cartridge puncturing ink feed tube disposed at the threaded end of the holder and having an exposed portion extending coaxially of the holder and provided with a threaded point; an ink cartridge having a threaded open end adapted to be threadedly coupled to the threaded end of the holder; a previous wall disposed interiorly of the cartridge and sealing the open end to form an ink reservoir, said wall being spaced from the open end of the cartridge a distance such in relation to the length of the exposed portion of the feed tube that upon initial threading of the holder and cartridge together the threaded point of the tube 70 is spaced from the wall, and the relationship in the 75

distance of said wall from the end of the cartridge and the length of the exposed portion of the tube being such that when the holder and cartridge are completely threaded together a portion of the threaded point of the feed tube is disposed in threaded ink sealing engagement with the wall and another portion projects beyond the wall and into the ink reservoir.

3. A cartridge type fountain pen comprising: a pen point holder having a threaded end, an ink feed tube in the holder having a cartridge puncturing portion extending coaxially of the holder, said cartridge puncturing portion provided with a threaded point with the pitch of the threads corresponding to the pitch of the threads at the threaded end of the holder, an ink cartridge having a threaded open end adapted to be threadedly coupled to the threaded end of the holder, a pervious wall disposed interiorly of the cartridge and sealing the open end thereof to form an ink reservoir, and said threaded point of the cartridge puncturing portion of the tube adapted to be tapped through the pervious wall of the cartridge and forming a seal therewith as the cartridge and holder are threaded together.

4. The invention as defined in claim 3 characterized in that said cartridge puncturing portion of the ink feed tube is threaded and tapered throughout its length.

5. The invention as defined in claim 4 characterized in that the feed tube is provided with a longitudinal passageway opening outwardly at the threaded end of the cartridge puncturing portion through the threaded side wall thereof.

6. A cartridge type fountain pen comprising: a pen point holder having a threaded end, an ink feed tube

disposed within the threaded end of the holder and extending coaxially thereof and having a tapering threaded point, an ink cartridge having a threaded end adapted to be threadedly coupled to the threaded end of the holder, a puncturable wall at the threaded end of the cartridge, said threaded point of the tube adapted to tap through said puncturable wall and form a seal therewith during and after threaded coupling of the cartridge and holder, and the axial position of said wall relative to the threaded end of the cartridge and the axial position of said threaded point relative to the threaded end of the holder being such that upon initial threading together of the cartridge and holder the tip of said point is spaced from the puncturable wall and upon complete threading together of the cartridge and holder said point of the feed tube extends in threaded ink-sealing engagement through the wall and therebeyond.
